(57) **CLAIM**

We claim the ornamental design for actuator overcap for a pressurized container, as shown.

DESCRIPTION

FIG. 1 is a right, top, rear perspective view of an actuator overcap for a pressurized container embodying our new design;

FIG. 2 is a right, top, front perspective view thereof;

FIG. 3 is a rear elevational view thereof;

FIG. 4 is a right side elevational view thereof, the left side being a mirror image thereof;

FIG. 5 is a front elevational view thereof;

FIG. 6 is a top plan view thereof;

FIG. 7 is a right, top, rear perspective view of a second embodiment of the actuator overcap shown in FIG. 1;

FIG. 8 is a right, top, front perspective view of the actuator overcap of FIG. 7;

FIG. 9 is a rear elevational view of the actuator overcap of FIG. 7;

FIG. 10 is a right side elevational view of the actuator overcap of FIG. 7, the left side being a mirror image thereof;

FIG. 11 is a front elevational view of the actuator overcap of FIG. 7;

FIG. 12 is a top plan view of the actuator overcap of FIG. 7;

FIG. 13 is a right, top, rear perspective view of a third embodiment of the actuator overcap shown in FIG. 1;

FIG. 14 is a right, top, front perspective view of the actuator overcap of FIG. 13;

FIG. 15 is a rear elevational view of the actuator overcap of FIG. 13;

FIG. 16 is a right side elevational view of the actuator overcap of FIG. 13, the left side being a mirror image thereof;

FIG. 17 is a front elevational view of the actuator overcap of FIG. 13; and,

FIG. 18 is a top plan view of the actuator overcap of FIG. 13.

The bottom of the actuator overcap forms no part of the claimed design. Likewise, the broken lines on the top of the actuator overcap form no part of the claimed design.

1 Claim, 6 Drawing Sheets
